GATE VALVE

William E. Lowrey and Clifford E. Anderson, Houston, Tex., assignors to ACF Industries, Incorporated, New York, N.Y., a corporation of New Jersey

Filed Apr. 15, 1965, Ser. No. 84,792

Term of patent 14 years

(Cl. D91—3)

FIGURE 1 is an elevational view of a gate valve, showing our new design.

FIGURE 2 is a right side elevation of the gate valve of FIGURE 1.

FIGURE 3 is a top view of the gate valve of FIGURE 1.

FIGURE 4 is a bottom view of the gate valve of FIGURE 1.

The left side elevational view of the gate valve is substantially as illustrated in FIGURE 2.

The dominant features of our design reside in the portions shown in full lines.

We claim:

The ornamental design for a gate valve, as shown and described.
